4 Claims. (Cl. 28—1)

The present invention concerns improvements in or relating to the crimping of yarn and has particular reference to crimping by the so-called stuffer-box process.

As is now well-known, the crimping of yarns is often desirable in order to increase their bulk and to give them a fuller and loftier handle than that which they possess in uncrimped form. Crimping has become one of the major processes in the field of yarn supply and, although it is sometimes carried out on yarns or slivers of staple fibre, it is normally carried out on continuous filament yarns and it has enabled them to be utilized in many textile articles in which traditionally only spun yarns were capable of being used. Such textile articles are for example knitted outerwear and carpets, whether the latter be of the cut or uncut pile type.

One of the now well-established crimping processes, for both spun staple yarns and continuous filament yarns, is the stuffer-box process above referred to, with which this invention is particularly concerned. In this process, which in its essentials dates back some fifty years, yarn is forced by feed rolls into a crimping chamber comprising a zone of compression in which a predetermined back-pressure is maintained, and the yarn is therein crimped and compacted. The yarn may either be forced out of the stuffer-box or be pulled out under tension, the latter method of removal providing a finer control over the process and hence of the characteristics of the crimped yarn, and enabling the process to be one in which yarn starts in a package and ends up in a package in a continuous manner.

It is sometimes possible for part or all of a filamentary structure to slip slightly between the rolls when the latter are being used to withdraw the filamentary structure from a supply or supplies thereof; and this is especially the case when, as is often desirable, there is a small clearance between the peripheries of the feed rolls at their closest point. Consequently, separate feed means are sometimes employed whose function is to withdraw the filamentary structure from its supply and to forward it to the feed rolls of the stuffer-box at a low tension when the risk of slipping will be greatly minimised if not completely obviated. The disadvantage of slipping may only be likely to be of great consequence when the filamentary structure being crimped comprises a plurality of multi-filament yarns and the slipping affects one or more of such yarns. In that event the composite crimped yarn withdrawn from the stuffer-box will comprise component yarns which have had an unequal crimp; and one effect of such unequal crimping will be that the composite yarn has a tendency to split up into its separate components, when employed, for example, as pile yarn in a tufted carpet. This splitting of the yarn into its components may not be desirable.

We have now found that a most convenient and effective means for forwarding a filamentary structure to a stuffer-box crimpler automatically at the correct rate and under a low, even or a negligible tension is provided by apparatus comprising rotatable forwarding means driven by contact with one of the feed rolls of the stuffer-box, the filamentary structure being led at least partly around such means and between it and the feed roll

2

prior to its entry between the nip of the feed rolls of the stuffer-box.

Accordingly the invention consists in a stuffer-box crimpler comprising feed rolls for forcing a filamentary structure therebetween and into a zone of compression, and having rotatable means for forwarding the filamentary structure to said feed rolls, which rotatable means is driven by contact with one of the said feed rolls, so that the filamentary structure is automatically and positively forwarded to the feed rolls at the same rate that it is forced into the zone of compression. The invention also consists in a process for crimping a filamentary structure comprising positively forwarding said structure automatically at the desired rate, and at a low, even or a negligible tension, to the feed rolls of a stuffer-box crimpler, and crimping the structure therein.

Preferably the forwarding means comprises a roll driven by peripheral contact with the stuffer-box feed roll and held in contact therewith by a spring or other like means. Preferably, also, such a driven roll has a peripheral surface composed of a material, such as rubber, having a high coefficient friction with the filamentary structure in order that the forwarding effect shall be a positive one.

25 The invention will now be described with reference to the accompanying drawing which is a diagrammatic side view of a stuffer-box crimpler and forwarding means according to one convenient embodiment of the invention.

The stuffer-box crimpler shown diagrammatically at 1 30 has driven feed rolls 3 and 5, whose peripheries are at their closest point some 3 thousandths of an inch apart, for forcing the filamentary structure 7 into the zone of compression within the stuffer-box where the structure, in this case a single yarn, is crimped. Bearing against 35 the periphery of feed roll 5, and pivoted about a point in the vertical plane of the nip of the feed rolls, is forwarding roll 9 having a point of contact with the periphery of feed roll 5 some 120° of arc clockwise from the nip of the feed rolls 3 and 5. The forwarding roll 40 9 has a peripheral surface of rubber, and is held in contact with feed roll 5 by means of spring 11 which is attached at one of its ends to an extension of arm 13 on which roll 9 is mounted, and at the other of its ends to a portion of the machine mounting. Yarn 7 is 45 led through guide 15 from a source of supply (not shown) and thence travels in contact with a portion of the periphery of roll 9 before being forwarded from the nip of rolls 5 and 9 at a low tension to the stuffer box. The 50 yarn may then travel continuously in contact with the portion of the periphery of roll 5 prior to entry into the stuffer-box, or it may intermittently be raised slightly clear thereof in a free loop, depending on whether there is any slippage between it and the rolls 3 and 5.

55 It will be seen, therefore, that according to the invention a means is provided for forwarding a filamentary structure, whether composed of a single or a plurality of component yarns or filaments, to a stuffer-box under a low, even or a negligible tension, such means being of a kind that automatically provides for the correct forwarding rate, owing to the fact that it is driven by contact with one of the feed rolls itself.

We claim:

1. Apparatus for crimping a continuous filamentary structure comprising: a crimping chamber; two fixed 65 closely-spaced feed rolls driven at a predetermined rate such that said structure when passed between them is forced into said chamber; and structure forwarding means comprising a third roll arranged so that said structure is in contact with a portion of the periphery of said third roll and is gripped between said third roll and one of said feed rolls, said third roll being driven by said one

feed roll such that said structure is positively forwarded by said third roll at the same rate as said predetermined rate at which it is forced into said chamber.

2. Apparatus according to claim 1, wherein said third roll has a peripheral surface of a material which has a high coefficient of friction with the filamentary structure.

3. A process for crimping a continuous filamentary structure comprising the steps of

- (a) positively withdrawing said structure from a supply thereof at a predetermined rate, 10
- (b) forwarding said structure at said rate to a pair of driven feed rolls,
- (c) forcing said structure between the nip of said feed rolls into a zone of compression,
- (d) resisting the emergence of said structure from said zone in order to crimp same therein, and 15
- (e) automatically positively maintaining the said predetermined rate the same as the rate at which said structure is forced into said zone of compression.

4. A process according to claim 3 wherein the structure is withdrawn from its supply and is forwarded to the feed rolls by being passed between the nip of a roll held in driven contact with the periphery of one of the said feed rolls.
